(57) **CLAIM**

The ornamental design for lollipop shaped thermometer, as shown and described.

DESCRIPTION

FIG. 1 is a perspective view of my new design for a lollipop shaped thermometer;

FIG. 2 is a top plan view thereof;

FIG. 3 is a right side elevation thereof;

FIG. 4 is a bottom plan view thereof;

FIG. 5 is a left side elevation view of my new design for a lollipop shaped thermometer;

FIG. 6 is a top plan view of my new design for a lollipop shaped thermometer with a transparent display, shown in a condition of use; and,

FIG. 7 is a bottom plan view of the transparent display thermometer as illustrated in FIG. 6, shown in a condition of use.

The broken lines are for illustration purposes only and form no part of the claimed designs.
